(57) CLAIM

The ornamental design for a peep housing, as shown and described.

DESCRIPTION

FIG. 1 is an upper right front perspective view of a peep housing showing my new design;

FIG. 2 is a front view thereof;

FIG. 3 is a rear view thereof in a condition of use;

FIG. 4 is a right side view thereof;

FIG. 5 is a left side view thereof;

FIG. 6 is a top view thereof; and,

FIG. 7 is a bottom view thereof.

The broken lines in FIG. 3 are included for the purpose of illustrating the environment only and form no part of the claimed design.
